HUDSON MAXIM, OF HOPATCONG, NEW JERSEY.

PROPELLION OF AUTOMOBILE TORPEDOES.

1,311,984.

Specification of Letters Patent.

Patented Aug. 5, 1919.

Application filed February 14, 1917. Serial No. 148,558.

To all whom it may concern:

Be it known that I, HUDSON MAXIM, of the borough of Hopatcong, county of Sussex, State of New Jersey, with post-office address Landing, New Jersey, have invented certain new and useful Improvements in the Propulsion of Self-Propelled or Automobile Torpedoes, of which the following is a specification.

10 The object of the invention is mainly to provide in a more efficient and practical manner than heretofore for the evaporation of water and the production of steam for actuating a turbine or other propelling means for driving torpedoes through the water.

Heretofore compressed air has been employed in torpedoes for the combustible atmosphere or supporter of combustion, and alcohol has mainly been employed as the 20 fuel, and the heat of combustion utilized for evaporating the water, and the products of combustion and steam employed for actuating a turbine or other engine for driving the torpedo.

25 In order to attain the maximum of speed and range, greater and greater air pressures and heavier and more expensive air flasks have been employed, and the water supply tank reduced to minimum of size and weight, 30 or water has been pumped from the sea during the run for the production of steam, instead of carrying the water on board, thereby consuming a portion of the useful energy for driving the torpedo in running the pump.

35 Four-fifths of the weight of air carried in the flask of compressed air is inert nitrogen, and this nitrogen is not only inert but also consumes heat to raise it to the required temperature as a motive fluid. By the employ-

40 ment of pure oxygen, according to my invention, I am able, however, to provide more than five times the amount of available energy in the same space and with the same pressure as is rendered available by the use of 45 compressed air, and by this means I may with practically the same apparatus as that employed in the usual form of torpedo, secure either five times the range now secured, or both greater speed and longer range, or I

50 may still secure greater speed and longer range than is attained by the usual torpedo with considerably less gas pressure, less weight of gas or air flask, and a flask of lighter weight and of cheaper construction.

55 Furthermore, I may employ a gas or air flask only two-fifths as large as the present

torpedo, or I may reduce the size and weight of the present air flask sufficiently to enable me to carry a very much larger explosive charge in the war-head. 60

When burning any fluid fuel in an atmosphere of oxygen under a pressure of 300 to 500 pounds to the square inch, the violence of the reaction of combustion is greatly increased above that which occurs under atmospheric pressure. 65

It is well-known that when acetylene or other fluid fuel is burned in an atmosphere of pure oxygen gas, the combustion is very violent, the heat developed very great and 70 very intense, while the size of the flame is comparatively small, being localized to a very circumscribed zone of combustion.

The difficulty of utilizing oxygen instead of compressed air in a torpedo for burning a 75 fuel and evaporating water to drive a turbine, is great, but by means of the present invention such trouble is entirely obviated by mixing water with a fuel such as acetone charged with acetylene, before burning it, 80 the presence of water serving to retard or lessen the violence of the combustion in proportion to the quantity of water employed.

It has been found that acetone possesses such a strong affinity for acetylene and such 85 a power of absorption of acetylene gas that even under atmospheric pressure it will absorb many times its own volume of the gas, while under increased pressure it absorbs correspondingly larger quantities, and that 90 when a pressure is employed sufficient to liquefy acetylene gas at a given temperature, the liquid acetylene and the acetone are miscible, or soluble in each other in all proportions, and that if and when the liquid 95 acetylene contains as small a quantity as ten per cent. of acetone, the liquid acetylene is rendered practically non-explosive.

Furthermore, I have found that acetone charged with acetylene gas to saturation, 100 even under atmospheric pressure, may be mixed with several times its weight of water, the acetone holding the acetylene in solution in the water, and the mixture burned like gasoline in an internal combustion engine, and that when charged with acetylene under a still higher pressure, the quantity of water that may be mixed with the acetone-acetylene fluid and burned, is considerably decreased, until a point is reached where the 105 acetone fails to hold all of the acetylene in solution in the water. 110

Acetylene being a gas very high in carbon and also an endo-thermic body, when burned in an atmosphere of pure oxygen, the reaction of combustion is still more violent than with other fluid fuels, the zone of flame still more circumscribed, and the heat still more intense.

I have found that when a certain proportion of water is added to a mixture 10 of acetylene and acetone, the zone of flame or combustion is greatly enlarged, the heat rendered much less intense and less local, while the quantity of heat evolved by the combustion remains the same, a portion of 15 the heat being absorbed, however, in the evaporation of the contained water. The more water that is added the more pronounced are these results, up to the point where enough water is added to prevent 20 combustion.

I have found, therefore, that in practising the present invention a certain and considerable proportion of water may with advantage be added to acetone charged with 25 acetylene, and burned for the production of a motive fluid consisting of the products of combustion of the acetylene and acetone and the steam produced, for actuating a turbine or other engine for driving a torpedo.

Furthermore, I have found that when a sufficient quantity of water cannot be held in solution in the acetone and acetylene mixture for this purpose without the products 35 of combustion being too hot and thereby liable to injure the engine, any desired smaller proportion of water may be mixed with the acetone-acetylene fuel and burned, and additional water admitted to the combustion chamber to be evaporated by the 40 excess of heat contained in the products of combustion over and above the heat required for the evaporation of the water contained in the fuel itself. When acetone 45 is charged with acetylene under pressure and the pressure relieved, a large proportion of the acetylene is released or distilled out of the acetone, leaving the acetone behind as a residuum.

50 Therefore, as acetylene gas is not miscible or soluble in water to any considerable extent, in order to place both the fuel tank and the water tank in the torpedo under equal pressure, I connect the top of the 55 fuel tank with the water tank and thereby permit the acetylene gas to escape from the acetone in the fuel tank and enter the space on top of the water in the water tank, thereby subjecting the water to the same 60 pressure as that exerted in the fuel tank.

As the fuel and water are drawn off and a larger space created both top of the water and the fuel, that extra space is continuously filled with the released acetylene, and the 65 pressure is thereby maintained substantially

undiminished until all or nearly all of both the fuel and the water are drawn off.

For the reason that the acetylene is distilled off from the acetone leaving the residual acetone behind in the fuel tank, I may 70 and sometimes do, especially in making try-out runs of torpedoes, draw off the acetylene from the top of the tank for supplying combustion for the evaporation of water instead of drawing off the acetone itself, 75 and after the run the residual acetone may be recharged with acetylene for another run.

When employing the acetylene gas in this manner it is necessary to employ an atomizer or mixer through which both the 80 acetylene gas and the water are passed immediately before entering the burner, in order to facilitate combustion and the evaporation of the water in the flame-blast. Also obviously, any other suitable fluid or 85 liquid fuel may be passed into the conduit or current of water and passed through the mixer and the mixture burned in the oxygen atmosphere of the combustion chamber. In this way very cheap fuel oils may be employed.

The combustion in this instance is very greatly enhanced and accelerated by the presence of acetylene gas in the mixing of water and other fuel. Obviously, then, this 95 invention provides a means both for the very inexpensive operation of torpedoes in peace practice, when maximum range or speed is not required, and in time of war a most effectual means for propelling torpedoes at a more considerable and yet permissible expense by the employment of acetone charged with acetylene unadulterated with any other fuel, in the manner I have 100 described.

When employing another fuel besides acetylene or acetone and acetone, especially when employing a heavy fuel oil, such as asphalt oil, as a fuel, I preferably admit a certain proportion of the oil into the path of 110 the mixture of acetylene, acetone and water, and then preferably pass the same through a mixing or atomizing device, preferably located near to the burner so that when the mixture enters the burner it is in an intimately commingled condition, and when the oxygen comes in contact with the fuel jet, effectual and satisfactory combustion 115 takes place.

When proceeding in this manner with the 120 combined use of a heavy fuel oil and a gaseous fuel, preferably acetylene, I may and sometimes do employ the acetylene alone in a gaseous state instead of combined with acetone. The acetylene gas commingles with the other fuel and water and thus serves as a torch or continuous igniter or accelerator of combustion of the heavy fuel.

When a gaseous fuel or a volatile liquid fuel is employed in conjunction with oxy- 125 130

gen, great care is necessary to prevent the escape of the oxygen and its commingling with the fuel, thus producing an explosive mixture. To obviate this danger I provide 5 an absolutely sealed joint by brazing or by soldering a fragile metallic cap or diaphragm over the outlet orifice, thereby closing the container of the oxygen. I may close the fuel container in like manner if desired, 10 at the same time temporarily supporting the cap against fracture from internal pressure by pressure externally applied until the torpedo is about to go into action.

With this general understanding of the 15 improvements, a detailed description of an apparatus adapted to carry them out will now be given with reference to the accompanying drawings, in which:

Figure 1, is a longitudinal sectional view 20 of so much of an automobile torpedo as is necessary to a proper description of the invention:

Fig. 2, is a cross-section of the same taken on the line 2, 2, of Fig. 1.

Fig. 3, is an enlarged central section of 25 the device for sealing the opening leading from either or all of the pressure-containing flasks or tanks.

Referring to said drawings, A, represents 30 the shell of an ordinary service torpedo, say for instance of the Whitehead type; B, the oxygen flask; E, E', the fuel tanks; and W, the water tank. Associated with these is the combustion chamber C, from which 35 leads a conduit D directing the mixed products of combustion and steam to a suitable turbine engine or other motor M, to drive the propeller shaft S, and also a water pump P.

40 The oxygen from the flask B, is led by a pipe or tube a, to a sealing device F, see Fig. 3, which tightly seals the outlet from the flask until just before the torpedo is to go into action and thus prevents the leakage of 45 oxygen and the consequent loss of pressure in the flask. This device consists of a casing 10 having a flange 11 adapted to be secured to the inner surface of the torpedo shell A. The nozzle end of the pipe a, is 50 screw-threaded into the lower end of the casing and is covered by a copper cap, thimble or diaphragm 12 that is brazed to the walls of the nozzle and flanged to be firmly seated and tightly squeezed between a shoulder on the pipe and a sharp-edged seat 2, on the casing immediately surrounding the nozzle and thimble. The head of the thimble is held firmly in place against the pressure in the pipe by the concaved face of the non- 55 rotating head 13, of a screw-threaded stem 14, the threads engaging similar threads in the casing. So long as the head is tightly held against the head of the thimble it is prevented from being fractured and no es- 60 cape of the gas occurs.

When, however, the torpedo is about to be used, the head 13, is raised by a proper tool entered through a perforation 3, in the shell and casing to rotate the threaded stem 14, whereupon the pressure immediately ruptures the head of the thimble so that the high pressure gas may pass outward through the pipe b.

From the sealing device F, the oxygen is led by a pipe b to the starting valve G, of 75 usual construction, opened during the movement of the torpedo through its launching tube by its valve lever g, striking a projection on the tube. From this valve the gas passes to an ordinary pressure-reducing 80 valve R, and thence under reduced pressure by a pipe H, to the combustion chamber C, at a point in proximity to the fuel burner N.

The fuel-containing tanks E and E', (one 85 or many may be employed) communicate with each other by a pipe v at their undersides, so that only one leading-off pipe I, need be used. The water tank W is provided with a leading-off pipe K, and its contents are held under the same pressure as that in the fuel tanks by a communicating pipe w, at the upper sides. The pipes K and L join at the union l, so that the fuel and water pass together to a stop valve O 95 and thence by a pipe I through a mixing chamber J to the burner N. The stem of the valve O has a lever e, connected by a rod i, to another lever c on the stem of the starting valve G, so that when said valve is opened, 100 the valve O will be simultaneously opened to allow the fuel and water to pass onward to the burner. The mixing chamber J, is provided with baffle plates j, to insure a more thorough commingling of the fuel and water 105 on their onward passage.

The fuel mixture may be ignited in the combustion chamber, in the presence of the oxygen supplied by the pipe H, by any suitable means, such, for instance, as an incandescent wire in circuit with a source of electricity U.

The products of combustion in a flame-blast, mingled with super-heated steam, pass through the combustion chamber C, thence 115 into the conduit D, carrying with them water admitted to the combustion chamber onward through baffle plates d, contained in the conduit D, whereby the additional water is instantly atomized and evaporated, and 120 the excessive heat contained in the products of combustion thereby utilized in the production of additional steam. Upon the operation of the motor, the pump P is actuated taking water from the sea and delivering it 125 through a pipe Q that terminates in the combustion chamber in a flattened nozzle q, in the path of the products of combustion from the burner, so that the water therefrom is immediately atomized and converted into

steam to augment and become thoroughly mixed with those products as they pass onward to operate the motor.

While the pump is supplying water to the combustion chamber, water may also be fed to the tank W by pipe s, leading from the pipe Q to the bottom of said tank. This pipe is controlled by a valve t opened in a manner similar to the valve O by a connection between their valve stems. Before the pump gets into full operation the same pipe s, may lead water from the tank W to the nozzle q.

The water tank W, may obviously need only be of a capacity to supply sufficient water for the starting of the motor or until in the operation of the motor the pump supplies the needed quantity of water to the flame or products of combustion.

Also, the water either with or without the separate tank W may be filled into the fuel tank and held by the fuel tank or tanks to be passed with the acetylene-charged acetone as a composite unit to the burner.

As the size of the flask due to the use of oxygen may be much reduced, the needed amount of water to be converted into steam to make a run may obviously be contained by a sufficiently large tank or tanks carried by the torpedo, and hence the necessity for the pump be avoided.

Instead of feeding the acetone charged with acetylene to the burner, the acetylene may be allowed to distil off from the acetone in the fuel tank or tanks, and accumulating in the top of the same may be led off by a pipe L', see dotted lines Figs. 1 and 2, and thence by pipes L and I to the burner. The acetone remaining in the fuel tank or tanks may be recharged with acetylene for further use.

It is obvious that the arrangement of the parts and the details of construction shown in the drawings may be widely varied without departing from the invention. Thus the starting valve may be differently constructed and operated. The starting and reducing valves may be contained by a single casing, and the sealing device casing may be cast integral with the head of the flask, thereby avoiding the connecting pipe. Changes may be made in the construction and form of the combustion chamber, the burner and the mixing chamber, and the sealing device is susceptible of modification. Other tanks may be added containing heavier fuel than acetylene to become mixed therewith and burnt in the manner herein set forth.

What is claimed is:

1. The process of producing a motive fluid for driving torpedoes which consists in commingling water with a fuel continuously burning the fuel in an atmosphere mainly of oxygen under pressure, and there-

by evaporating the water and then utilizing the products of combustion and steam combined for propelling a torpedo.

2. The method of driving self-propelled torpedoes which consists in commingling water and oxygen with a fuel, burning the fuel, atomizing and evaporating water by the flame-blast of the products of combustion; and then utilizing the mixed products of combustion and steam to actuate a propelling means for driving a torpedo through the water.

3. The herein-described method of producing a motive fluid for driving torpedoes which consists in mixing water with acetylene, burning the acetylene in oxygen, evaporating water with the products of combustion, and then driving the torpedo by means of the escaping steam and products of combustion.

4. The herein-described method of producing a motive fluid for driving torpedoes, which consists in mixing water with acetylene, burning the acetylene gas in oxygen together with another fuel, evaporating water by the flame-blast of the products of combustion, and then utilizing the steam and products of combustion for actuating means for propelling the torpedo.

5. The herein-described method of producing a motive fluid and driving a torpedo with the same, which consists in commingling water and a gaseous fuel, then burning the same in an atmosphere of oxygen and utilizing the products of combustion and the steam produced as a propelling means for the torpedo.

6. The herein-described method of producing a motive fluid and driving a torpedo with the same, which consists in commingling water and a gaseous fuel, then burning the same in an atmosphere of oxygen, utilizing the excess of heat of the products of combustion and contained superheated steam for the evaporation of additional water, and then utilizing the products of combustion of the steam produced as a propelling means for the torpedo.

7. The herein-described method of producing a motive fluid and driving a torpedo with the same, which consists in commingling a gaseous fuel and a non-gaseous fuel with water, burning the same in an atmosphere rich in oxygen and utilizing the products of combustion and the steam as a propelling means for driving a torpedo.

8. The herein-described method of producing a motive fluid for driving a torpedo, which consists in charging a non-gaseous fuel with a fuel gas and burning the same to evaporate water and utilizing the products of combustion to actuate a turbine or other means for driving a torpedo.

9. The herein-described method of producing a motive fluid for driving a torpedo,

which consists in mixing acetylene with water and burning the mixture in an atmosphere of air and oxygen.

10. The herein-described method of producing a motive fluid for propelling a torpedo, which consists in mixing acetylene and another fuel with water and burning the same in an atmosphere of oxygen or air and oxygen.

11. The herein-described method of producing a motive fluid, which consists in mixing with water a suitable solvent containing acetylene and capable of holding the acetylene in solution in the water, and then burning the mixture and utilizing the products of combustion and the steam produced for actuating means for propelling the torpedo.

12. The herein-described method of securing against escape compressed air or oxygen in a torpedo prior to its utilization for driving a torpedo, together with means for effecting its utilization at the proper moment, which consists in effectually closing the exit orifice by means of an impervious metallic diaphragm or partition, united securely to the walls of the orifice, the said diaphragm being capable of being ruptured by the pressure of the compressed air or oxygen, and normally held against disruption by a support or by pressure externally applied, and means for opening the orifice to free the oxygen by removing the external pressure and permitting the diaphragm to be disrupted by the pressure of the contained oxygen or air.

13. In an automobile torpedo, the combination of oxygen, fuel and water containers, a combustion chamber, means for admitting oxygen, fuel and water to said chamber on the launching of the torpedo, a suitable

motor, a conduit leading the mixed products of combustion and steam to the motor and a pump operated by the motor supplying water to the combustion chamber.

14. In an automobile torpedo, the combination of oxygen, fuel and water containers, a mixing chamber for the fuel and water, a combustion chamber, a conduit from the mixing chamber to the combustion chamber, a motor and a conduit leading the mixed products of combustion and steam from the combustion chamber to the motor.

15. In an automobile torpedo, the combination of oxygen, fuel and water containers, a mixing chamber for the fuel and water, a combustion chamber, a conduit from the mixing chamber to the combustion chamber, means for feeding other water to said combustion chamber, a motor and a conduit for leading the mixed products of combustion and steam from the combustion chamber to the motor.

16. In an automobile torpedo, the combination of oxygen, fuel and water containers, a mixing chamber for the fuel and water, a combustion chamber, a conduit from the mixing chamber to the combustion chamber, means for feeding other water to the combustion chamber to be converted into steam, a motor, means for mixing the products of combustion and steam and a conduit leading said mixture to the motor.

In testimony whereof I have signed my name to this specification in the presence of two subscribing witnesses.
